CLAIM

The ornamental design for a portable gaming apparatus, as shown and described.

DESCRIPTION

FIG. 1 is a perspective view of the portable gaming apparatus showing my new design;

FIG. 2 is a front view of the front component of the portable gaming apparatus that is situated opposite the rear foot stand component;

FIG. 3 is a rear elevation view of the portable gaming apparatus;

FIG. 4 is a left side elevation view thereof;

FIG. 5 is a right side elevation view thereof;

FIG. 6 is a top plan view thereof; and,

FIG. 7 is a bottom plan view thereof.

The broken lines depict unclaimed features of the portable gaming apparatus that form no part of the design claim but are shown for purposes of illustration.
